United States Patent Office

Des. 180,333

Patented May 21, 1957

180,333

ROLLER SKATE

Charles E. Jones, Chicago, and William G. Crowle, Berwyn, Ill., assignors to Manning Manufacturing Corporation, Chicago, Ill., a corporation of Illinois

Application July 23, 1956, Serial No. 42,350

Term of patent 14 years

(Cl. D34—14)

Fig. 1

Fig. 2

FIG. 3

Figure 1 is a perspective view of a roller skate, showing my design;

Figure 2 is a bottom view thereof;

Figure 3 is a side view thereof; and

Figure 4 is a rear view thereof.

We claim:

The ornamental design for a roller skate, substantially as shown.
